Specification for Design.

Patented July 28, 1914.

Application filed April 18, 1914. Serial No. 832,980. Term of patent 7 years.

To all whom it may concern:

Be it known that we, JOSEPH W. MACLAREN, a citizen of the United States, residing in the city of New York, borough of Brooklyn, in the county of Kings and State of New York, and EMIL SPECK, a citizen of the Republic of Switzerland, residing in Passaic, in the county of Passaic and State of New Jersey, have invented a new, original, and ornamental Design for Ribbon, and Particularly for Brocaded Woven Ribbon, of which the following is a specification, reference being had to the accompanying drawing, forming part thereof.

The figure is a plan view of a portion of ribbon showing our new design.

We claim:

The ornamental design for ribbon and particularly for brocaded woven ribbon, as shown.

JOSEPH W. MACLAREN.
EMIL SPECK.
